UNITED STATES PATENT OFFICE.

McMASTER SYLVESTER BLACKBURN, OF SAN ANTONIO, TEXAS, ASSIGNEE TO McMASTER SYLVESTER BLACKBURN AND J. S. ARRINGTON, TRUSTEES FOR THE PETROLEUM ENGINEERING COMPANY, A COMMON-LAW TRUST COMPANY.

AUTOMATIC PUMP CONTROL.

Application filed April 30, 1923. Serial No. 635,627.

To all whom it may concern:

Be it known that I, McMaster Sylvester Blackburn, a citizen of the United States, residing at San Antonio, in the county of Bexar and State of Texas, have invented certain new and useful Improvements in Automatic Pump Controls; and I do declare the following to be a full, clear, and exact description of the invention, such as will enable others skilled in the art to which it appertains to make and use the same.

My invention relates to improvements in devices and methods for controlling well pumps and more particularly to controls for oil well pumps, one object of the invention being to provide means controlled by the quantity of liquid in the well, for automatically throwing the pump out of operation when the liquid level has descended to a predetermined extent, and for automatically restoring the pump to an operative condition when the liquid lever has been restored.

A further object of the invention is to throw the pump out of or into operation by unseating its standing valve or permitting it to seat, as occasion may be, without interfering with stroking of the traveling valve.

A still further object of the invention is to provide an automatic control which is controlled by the hydrostatic pressure in the well, normally acting to hold a standing valve opening stem in a balanced inoperative position, but acting also to shift said stem to an operative position when the balance is overcome by lowering of the liquid level to a predetermined extent.

A still further object is to provide novel means for holding the valve opening stem against movement until a predetermined time and for then permitting movement of said stem, insuring rapid motion thereof.

A still further object is to provide a controlling means which may be readily attached to the working barrel of an ordinary oil well pump without making alterations in the pump structure.

Yet another object is to provide a construction which will reduce resistance to the oil entering the well and will consequently obtain the same result as those now obtained by well packing, namely, increased production.

With the foregoing and numerous minor

objects in view, the invention resides in the novel subject matter hereinafter described and claimed, the description being supplemented by the accompanying drawings.

Figure 1 is a vertical sectional view showing the preferred form of my invention connected with the working barrel of an oil well pump, disclosing the normal relation of parts.

Figure 2 is a duplicate of Fig. 1 with the exception that it illustrates the manner in which the control device automatically unseats the standing valve when the liquid level in the well has lowered to a predetermined extent.

Figures 3, 4 and 5 are horizontal sectional views on lines 3—3, 4—4 and 5—5 of Fig. 1.

Figures 6 and 7 are views similar to Figs. 1 and 2 but illustrating a different form of construction.

Figures 8, 9 and 10 are horizontal sectional views on the lines 8—8, 9—9 and 10—10 of Fig. 6.

Figure 11 is a vertical sectional view showing a slight modification over the construction disclosed in Figs. 1 to 5.

Figures 12 and 13 are vertical sectional views showing different positions of parts and illustrating a still further form of construction.

Figures 14, 15 and 16 are horizontal sectional views as indicated by the lines 14—14, 15—15 and 16—16 of Fig. 12.

Figure 17 is a vertical sectional view showing yet another form of construction.

In the form of construction shown in Figs. 1 to 5, the numeral 1 designates the usual working barrel of an oil well pump, said barrel being provided with the usual standing valve 2 and standing valve seat 3 at its lower end. The numeral 4 designates a coupling which ordinarily connects the working barrel with a perforated tube, this tube being indicated in the drawings by the numeral 5, but being disposed at a lower point than usual, due to the fact that the controlling means for the standing valve 2 is interposed between the working barrel 1 and said tube 5.

The numeral 6 designates a body whose upper end is threaded into the coupling 4, while its lower end is threaded upon the tube 5, said body containing a chamber 7 across which a movable partition 8 extends, said

partition being preferably in the form of a diaphragm as shown. This diaphragm is connected with an upright stem 9 which extends into closely spaced relation with the 5 standing valve 2 as shown in Fig. 1, and the arrangement of parts is such that the partition 8 normally stands in the position shown in Fig. 1 so that said standing valve 2 may operate in the usual manner. When however, 10 the quantity of liquid in the well reaches a predetermined degree, the partition 8 is automatically forced upwardly as indicated in Fig. 2 and hence the standing valve 2 is automatically raised from its seat 15 and held in this position, thus throwing the pump out of operation while permitting its traveling valve (not shown) to continually stroke. This causes "slushing" of the liquid through the lower end of the pump and 20 through the control apparatus and serves not only to prevent the accumulation of sand, by washing it out, but acts also to agitate the liquid in the well, thereby preventing paraffining. This automatic unseating 25 of the standing valve also possesses numerous other advantages which will be herein-after entered into more fully. The valve remains open until the quantity of liquid in the well has again increased to such an extent as to make it advisable to again throw 30 the pump into play. Then, the partition 8 is automatically forced down, permitting the standing valve 2 to operate and consequently again restoring the pump to an operative 35 condition.

The portion of the chamber 7 below the partition 8, is in communication with the liquid containing space within the usual well casing 10, while the portion of said chamber 40 above said partition, communicates with the liquid intake of the working barrel 1 and also communicates with the interior of a liquid containing sleeve 11 which rises from the body 6 around the working barrel 1 and 45 is preferably of approximately twenty feet in length. The upper end of the sleeve 11 is open to receive liquid from the well and it will be seen from Fig. 1 that as long as the liquid level is above the sleeve, the hydrostatic pressure above and below the partition 50 8, is substantially balanced so that the stem 9 may be held down under the influence of a weight 12 or other desired means with which it may be provided. When the liquid 55 level in the well, reaches the upper end of the sleeve 11 and this sleeve can no longer fill with liquid, the level of liquid within the sleeve will of course lower as seen in Fig. 2, thus decreasing the downward pressure on 60 the partition 8 with the result that it is overbalanced by the upward pressure below said partition, causing upward movement of the partition and the stem 9 to effect an opening of the standing valve 2. The valve will 65 remain open until the liquid level in the well

has again risen to such extent as to fill the space within the sleeve 11, whereupon the balance of pressure at opposite sides of the partition 8 is restored and the stem 9 will be lowered under the influence of the weight 70 12.

In the preferred form of construction, the body 6 includes a cup-like lower section 13 having a depending flange 14 into which the tubing 5 is threaded, said section having an 75 internal shoulder 8' spaced above its bottom, against which the edge portion of the diaphragm 8 is clamped by an upper dome-like body section 15 which is threaded into the lower section 13. The upper end of the body 80 section 15 is formed with ports 16 and a guide opening for the stem 9 and the side wall of this section has additional ports 17 by means of which the portion of the chamber 7 within this section of the body, communicates with the sleeve 11, this sleeve being threaded around the upper end of the section 13, as indicated at 18.

To place the lower end of the chamber 7 in communication with the liquid containing 90 space of the well, I have shown vertical ports 19 formed through its bottom 20. This bottom is also formed with a central opening receiving a sleeve 21 on the stem 9. This sleeve is connected at its upper end to the 95 diaphragm or partition 8 and the stem 9 may be adjusted through said sleeve and held in adjusted position, by means of nuts or the like 22. The sleeve is preferably formed with a stop shoulder 23 to strike the bottom 100 20 of the body section 13 and limit the downward movement of the stem under the influence of the weight 12, thereby preventing possible injury to the diaphragm. I also prefer to provide the lower end of the sleeve 105 21 with a nut 24 or other projecting shoulder to strike the lower side of the bottom 20 and limit the upward movement of the stem 9 and associated parts.

It is desirable that the stem 9 shall be held 110 against movement until the pressure at one side or the other of the partition or diaphragm 8, has been reduced to a predetermined extent, and I have shown the preferred means of carrying out this end, in the 115 form of spring-pressed balls 25 mounted within bores 26 in the bottom 20, said balls being engageable with grooves or notches 27 in the sleeve 21. Plugs 28 are preferably threaded in the outer ends of the bores 26 120 for the purpose of adjusting the tension of the springs 29 which force the balls 25 normally inward. By this arrangement, the balls may be made to hold the sleeve 21 and associated parts against movement until the force acting to move them has reached a predetermined strength, whereupon the springs 29 will be immediately overcome and a quick 125 operation of parts will take place.

In the form of construction shown in Figs. 130

6 to 10 inclusive, I have shown a hollow body 6^a threaded in the coupling 4^a of the working barrel 1^a and a sleeve 11^a corresponding to the sleeve 11, rises from said body 6^a in spaced relation with the coupling 4^a and working barrel 1^a. The space within this sleeve 11^a communicates with the lower end of a chamber 7^a in the body 6^a, by means of a plurality of vertically positioned ports 17^a formed in 10 the peripheral portion of the body 6^a, while the upper portion of said chamber 7^a, which communicates with the coupling 4^a is in communication with the liquid space around the sleeve 11^a, by means of ports 19^a. A suitably 15 weighted and guided stem 9^a is mounted within the body 6^a and is connected with a movable partition or diaphragm 8^a which extends across the chamber 7^a below the ports 19^a. Spring-pressed balls or the like 25^a are 20 shown for yieldably holding the stem 9^a in either position, and I have shown these balls mounted in bores formed in a web 20^a which extends across the chamber 7^a and is formed with suitable ports 30 by means of which the 25 upper and lower ends of the chamber 7^a communicate with each other.

The construction just described, operates reversely from that illustrated in Figs. 1 to 5. As long as the liquid in the well is 30 above the upper end of the sleeve 11^a, this sleeve will be filled and consequently the portion of the chamber 7^a below the diaphragm or partition 8^a will also be filled and the liquid will exert an upward pressure on said 35 diaphragm or partition. Similarly, the liquid around the sleeve 11^a which enters the upper portion of the chamber 7^a will exert a corresponding downward pressure on the partition or diaphragm and will thus sub- 40 stantially counterbalance the same so that the weight 12^a of the stem 9^a may normally lower the latter away from the standing valve 2^a, this relation of parts being shown in Fig. 6. As soon as the liquid level lowers below 45 the upper end of the sleeve 11^a and recedes beyond this level as shown in Fig. 7, the downwardly acting pressure on the dia- phragm or partition 8^a is decreased, with the 50 result that the upwardly acting pressure will raise said diaphragm or partition and cause the stem 9^a to open the valve 2^a as shown clearly in the figure last referred to.

In the construction last considered, the body 6^a preferably consists of a main upper section 15^a which is threaded into the coupling 4^a and carries a sleeve 11^a, and a lower tubular section 13^a threaded into the lower end of the section 15^a. The lower end of the section 13^a is closed by a cap 31 so that the lower end of the chamber 7^a cannot communicate with the liquid space around the sleeve 11^a and body 6^a, and if desired this cap may be provided with means to connect it with a tubing such as that above referred to by the 60 numeral 5.

The construction illustrated in Fig. 11 is very similar to that shown in Figs. 1 to 5. In this view, 1^b designates the working barrel, 2^b indicates the standing valve, 4^b has reference to the coupling by means of which the body 6^b is connected to said working barrel, 13^b designates the lower section of this body, and 15^b has reference to the upper section which is threaded into the coupling 4^b. The body 6^b carries a sleeve 11^b rising 70 therefrom around the working barrel 1^b and contains a standing valve opening stem 9^b which is connected with a movable partition 8^b in the liquid containing chamber 7^b of the body 6^b. This partition is in the form of a piston operating in a cylindrical extension 14^b which depends from the body section 13^b, the lower end of this extension being threaded upon the usual perforated tube 5^b. Spring-pressed balls or other detents 25^b are 80 provided for holding the stem 9^b either raised or lowered and these spring-pressed devices are mounted in a web 20^b which extends across the body 6^b and is formed with ports 19^b establishing communication 85 between the upper and lower ends of the chamber 7^b. By means of these ports 19^b and ports 17^b in the body section 15^b, the portion of the chamber 7^b above the piston or movable partition 8^b communicates with the interior of the sleeve 11^b, while the portion of said chamber below the piston is in communication with the portion of the well around said sleeve and associated parts by 90 means of the perforations in the tube 5^b. It thus follows, that a substantial balance of parts normally takes place, permitting the weight 12^b to lower the stem 9^b and thereby allowing proper operation of the standing valve 2^b. When the liquid level lowers sufficiently however, the liquid within the sleeve 11^b is pumped out to some extent and consequently the downward pressure on the piston 8^b is decreased, with the result that the upward pressure thereof will move said piston and the stem 9^b to unseat the standing valve 2^b, as shown in Fig. 11. 105

In Figs. 12 to 16, a form of construction has been shown which relies on spring pressure for opening the standing valve 2^c. At 6^c, I have shown a body consisting of a lower section 13^c, closed at its sides and ends with the exception of ports 32 in its side wall, and an upper section 15^c threaded on said lower section and having an adjustable 110 threaded connection 33 with the coupling 4^c at the lower end of the working barrel 1^c, the side wall of said section 15^c having liquid inlet ports 34. A stem 9^c rises from the diaphragm 8^c through a suitable guide opening in the upper end of the body section 13^c and extends into operative relation 115 with the standing valve 2^c. This stem is provided within the body section 15^c with a collar 35 against which a coiled spring 36 120

125

130

thrusts upwardly, but the pressure of liquid acting downwardly upon the diaphragm 8^c normally prevents this spring from operating, as will be seen by reference to Fig. 12, 5 but when this pressure decreases by lowering of the liquid level in the well, as indicated in Fig. 13, the spring 36 comes into play. Spring-pressed balls or other detents 25^c however are employed to hold the stem 9^c 10 either raised or lowered until the force tending to move the same has become strong enough to effect a quick movement. Thus, as with the other forms of construction, it is insured that the standing valve shall 15 not be held at a partially opened position.

While the ports 32 might communicate directly with the liquid space of the well, I prefer to provide the upper body section 15^c with a depending sleeve 37 spaced outwardly 20 from the lower section 13^c and coupled at its lower end to a perforated tube 5^c by a suitable coupling ring 38.

As illustrated in Fig. 17, it is possible to effect an opening of the standing valve by 25 means of a float or a plurality of floats. In the construction shown in this view, a ported tubular body section 15^d is threaded into the coupling 4^d at the lower end of the working barrel 1^d and carries a lower body section 13^d 30 through which a stem 9^d extends for opening the standing valve 2^d, the lower end of this stem having a weight 12^d. The body section 13^d contains spring-pressed detents 25^d for yieldably holding the stem either 35 raised or lowered and I prefer that this body section shall connect with a perforated tube 5^d. A pair of suitable levers 40 have been shown suitably connected at their inner ends with the stem 9^d as indicated at 41 40 while their outer ends have eyes 42 slidably receiving rods 43 which depend from a tubular float 44 which surrounds the lower end of the working barrel 1^d, said float in practice, being considerably longer than shown, 45 as is also true of the rods 43. I have shown these rods provided with upper shoulders 45 to strike the eyes 42 when the float lowers, and also equipped with lower shoulders 46 to similarly engage said eyes when the float 50 raises. By employing this construction, it will be seen that with the liquid at a predetermined height in the well, the stops 46 will be in engagement with the eyes 42 of the 55 levers 40 and the stem 9^d will be lowered out of engagement with the standing valve 2^d. When the liquid level in the well recedes however, the upper stops 45 will strike the eyes 42 and will thus rock the levers 40 and 60 shift the stem 9^d upwardly, thereby opening the valve 2^d as depicted in Fig. 17.

All forms of my invention are automatic in all respects and are very desirable, and although the numerous advantages will be apparent to those skilled in the art, it may

be well to briefly set forth some of these 65 advantages, reference being made more particularly to oil well pumps, in the following.

The invention will automatically control the stopping and starting of the pump and will absolutely prevent the oil from being 70 cut by keeping a few feet of oil always over the standing valve, the controlling means being set to stop the operation of the pump when there remains from three to six feet of oil over the standing valve. The invention will increase the production of the an 75 oil well by relieving the pressure therein, by keeping the head pumped off, and it will be seen that paraffining or corroding is retarded, as the standing valve is opened before the oil recedes below the traveling valve and thus the oil is continually agitated, as long as the standing valve remains open. The life of the cup leathers of the pump is 80 greatly prolonged by keeping them constantly immersed and the possibility of pumping air with its consequent loss by volatilization is overcome. The device prevents the loss of a tubing of oil when the 85 pump is being removed from the well, as the standing valve is then held open and the contents of the working barrel and the tubing can bleed therethrough. It lessens the 90 labor of looking after the wells and relying upon such labor to stop and start the pumps and permits continual balanced operation 95 of the central power plant which cannot be obtained when the pumps are cut off or on when necessary. Also, attention may be directed to the fact that if desired, the movement of the stem 9, 9^a, etc., may be used to 100 control an electrical switch for any desired purpose.

Attention is directed to the fact that the 105 forms of the invention embodying the spill-over tube 11, 11^a and 11^b, provide for increased production from wells previously yielding poorly. This result is due to the fact that the column of oil between the tube 11, 11^a or 11^b and the well casing, which column must be lifted by the oil entering the well, is much smaller in horizontal area and consequently lighter than the column to be 110 lifted would be, if it filled the entire space between the well casing and working barrel 1. Thus, by enlarging the pump adjacent the producing strata, I diminish resistance to the incoming oil and the latter may enter the well more easily and rapidly, hence increasing production and getting the same result as now obtained by the expensive and laborious well packing methods.

Excellent results have been obtained from 115 the use of the invention and the details disclosed are therefore preferably followed, but it is to be understood that the present disclosure is principally for purpose of illustration and that within the scope of the inven- 120 125

tion as claimed, numerous changes may be made.

I claim:

1. The combination with a well pump having a standing valve; of means controlled by the quantity of liquid in the well for automatically holding said standing valve open when the liquid level has lowered to a predetermined extent.
2. The combination with a well pump having a standing valve; of means controlled by the quantity of liquid in the well for automatically holding said standing valve open when the liquid level has lowered to a predetermined extent, and for automatically releasing said valve when the liquid level is restored.
3. Controlling means for a well pump having a standing valve, comprising a vertical stem whose upper end is adapted to be normally spaced below the standing valve, guiding means for said stem, and means controlled by the quantity of liquid in the well for automatically raising said stem and holding the standing valve open when the liquid has lowered to a predetermined extent, and for automatically lowering said stem when the liquid level has been restored.
4. A structure as specified in claim 3; together with yielding means for resisting movement of said stem to a predetermined degree and for then suddenly releasing the same.
5. The combination with a well pump having a standing valve; of hydrostatically controlled means for automatically holding said standing valve open when the liquid level lowers to a predetermined extent and for again releasing said standing valve when the liquid level is restored.
6. The combination with a well pump having a standing valve; of hydrostatically balanced means for automatically holding said standing valve open when its balance is impaired by lowering of the liquid.
7. The combination with a well pump; of means including a movable member for automatically throwing the pump out of operation, and means for holding said throw-out means normally against movement, comprising means controlled by the liquid level in the well into which the pump extends, for maintaining substantially balanced hydrostatic pressure at opposite sides of said member until the liquid in the well lowers to a predetermined extent.
8. In combination with means for throwing a well pump out of action including a movable member; means for normally holding said throw-out means against operation, comprising means controlled by the liquid level in the well into which the pump extends, for maintaining a substantially balanced hydrostatic pressure at opposite sides

of said movable member until the liquid in the well lowers a predetermined extent.

9. Controlling means for a well pump having a standing valve, comprising an opening device for the valve, a liquid chamber having a movable partition connected with said opening device, and means for maintaining substantially uniform hydrostatic pressure in said chamber at opposite sides of said partition until the liquid level has lowered to a predetermined extent in the well and for then effecting a reduction of pressure at one side of said partition to move the latter and open the standing valve.

10. Controlling means for a well pump having a standing valve, comprising an opening device for the valve, a liquid chamber having a movable partition connected with said opening device, and a liquid container filled from the liquid in the well and communicating with said chamber at one side of said partition, said chamber being adapted for communication with the liquid space of the well at the other side of the partition to maintain a substantially uniform hydrostatic pressure at both sides of said partition, the action of the pump serving to destroy the uniformity of pressure after the liquid level in the well has reached the inlet of said container, thereby effecting movement of said partition and said valve opening device to open the standing valve.

11. Controlling means for a well pump having a standing valve at the lower end of its working barrel, comprising a body adapted for connection to the lower end of the working barrel and formed with a liquid chamber, one end of said chamber being adapted for communication with the liquid space around the body, a liquid containing sleeve rising from said body to surround the working barrel and open at its upper end to be filled with liquid from the well, one end of said chamber being in communication with said sleeve, a movable partition across said chamber, and a standing valve opening stem rising from said partition for close relation with the standing valve, one end of said chamber being adapted for communication with the liquid inlet of the working barrel.

12. Controlling means for a well pump having a standing valve at the lower end of its working barrel, comprising a body adapted for connection to the lower end of the working barrel and formed with a liquid chamber, the lower end of said chamber being adapted for communication with the liquid space around the body, a liquid containing sleeve rising from said body to surround the working barrel and open at its upper end to be filled with liquid from the well, the upper end of said chamber being in communication with said sleeve and

adapted to communicate with the liquid inlet of the pump, a movable partition across said chamber, and a standing valve opening stem rising from said partition for close relation 5 with the standing valve.

13. The method of manipulating a well pump having a traveling valve and a standing valve, consisting in opening the standing valve when the liquid in the well has 10 lowered to a predetermined extent, operating the traveling valve and holding the standing valve open until the liquid level in the well rises to a predetermined extent, closing the standing valve and continually 15 operating the traveling valve.

14. The combination with a well pump; of control means for said pump, having a movable member controlling its operation,

and means controlled by the liquid level in the well in which the pump is used, for 20 maintaining a substantially balanced hydrostatic pressure at opposite sides of said movable member until the liquid in the well lowers to a predetermined extent.

15. The combination with well pump cut-off means having a movable member controlling its operation; of means controlled by the liquid level in the well in which the pump is used, for maintaining a substantially balanced hydrostatic pressure at opposite sides of said movable member until the liquid in the well lowers to a predetermined extent.

In testimony whereof I have hereunto affixed my signature.

McMASTER SYLVESTER BLACKBURN.
